The ornamental design for a LED luminaire, as shown and described.

DESCRIPTION

FIG. 1 is a front perspective view of a LED luminaire showing our new design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is an enlarged view of section 9 from FIG. 6.

The broken lines on FIG. 6 labeled as "9" are included to indicate the point at which the enlarged view of FIG. 9 is cut off and form no part of the claimed design.

All other broken lines in the drawings illustrate portions of the LED luminaire that form no part of the claimed design.
